CLAIM

The ornamental design for a child's lap desk and blackboard, as shown and described.

DESCRIPTION

FIG. 1 is a top plan view of a child's lap desk and blackboard showing my new design.

FIG. 2 is an end elevational view.

FIG. 3 is a side elevational view; and

FIG. 4 is a perspective view showing the top partly open to give access to the interior storage compartment. The side and end not shown are the same as those shown.

FIG. 1FIG. 2FIG. 3FIG. 4
